2 Claims

ABSTRACT OF THE DISCLOSURE

Certain novel ring-substituted benzenesulfhydroxamic acids and esters, useful as herbicides.

BACKGROUND OF THE INVENTION

Field of the invention

This invention relates to a novel class of benzenesulfhydroxamic acids and esters, substituted on the ring with a secondary amino and two nitro moieties, which exhibit high herbicidal activity.

Description of the prior art

The herbicidal ring-substituted benzenesulfhydroxamic acids and esters of this invention have not previously been disclosed nor is any reference known which would anticipate them. U.S. Pats. 3,398,180 and 3,492,323 disclose a series of N-(2-propynyl)oxysulfanilamides substituted in two unspecified positions on the ring by a series of different functional groups including dialkylamino and nitro, which are useful as flavoring agents and chemical intermediates. Other related art is U.S. Pat. 3,367,949 which discloses a series of substituted 3,5-dinitrosulfanilamides as herbicides.

SUMMARY OF THE INVENTION

A new series of benzenesulfhydroxamic acids and esters substituted in the para position, relative to the sulfhydroxamic acid or ester moiety, with a secondary amino moiety and in the two meta positions with nitro moieties have been discovered. These novel compounds have shown high herbicidal activity in the control of several economically important species of grasses and broad leaved weeds.

The invention, accordingly, is a new class of benzene sulfhydroxamic acids and esters, their use as herbicides and herbicidal formulations containing them.

DESCRIPTION OF THE PREFERRED EMBODIMENTS

The novel compounds of this invention can be described by the general Formula I

wherein R¹ and R² are the same or different and each is alkyl of up to 4 carbon atoms, alkenyl of up to 4 carbon atoms, or cycloalkyl of up to 6 carbon atoms; R³ is hydrogen, alkyl of up to 4 carbon atoms, alkenyl of up to 4 carbon atoms, a lower alkali metal ion (Na, K or Li), a quaternary ammonium group wherein the cationic nitrogen is substituted with up to 4 alkyl groups each containing up to 3 carbon atoms or

wherein R⁵ is hydrogen, alkyl of up to 4 carbon atoms, alkenyl of up to 4 carbon atoms, cycloalkyl of up to 6

2

carbon atoms, —OR⁶ wherein R⁶ is alkyl of up to 4 carbon atoms; —NR⁷R⁸ wherein R⁷ is hydrogen and R⁸ is alkyl of up to 4 carbon atoms, Q is oxygen or sulfur, with the proviso that when Q is oxygen, R⁴ is hydrogen, alkyl of up to 4 carbon atoms, cycloalkyl of up to 6 carbon atoms or

10 wherein R⁹ is hydrogen, alkyl of up to 4 carbon atoms, alkenyl of up to 4 carbon atoms or —OR⁶ wherein R⁶ is as described above and when Q is sulfur R³ is

15 wherein R⁵ is as described above and R⁴ is alkyl of up to 2 carbon atoms wherein all the hydrogens have been replaced by chlorine or fluorine.

20 Exemplary species of the class of the invention include: tetramethylammonium salt of 4-(dipropylamino)-N-hydroxy-3,5-dinitrobenzenesulfonamide
4-(dipropylamino)-N-butoxy-N-butyl-3,5-dinitrobenzenesulfonamide
25 4-(dipropylamino)-N-allyloxy-N-ethyl-3,5-dinitrobenzenesulfonamide
N-(4-(dipropylamino)-3,5-dinitrobenzenesulfonyl)-N-methoxyformamide
30 4-(dipropylamino)-N-formyloxy-N-methyl-3,5-dinitrobenzenesulfonamide
N-(4-(dipropylamino)-3,5-dinitrobenzenesulfonyl)-N-methoxycrotonamide
N-(4-(dipropylamino)-3,5-dinitrobenzenesulfonyl)-N-35 allyloxyacrylamide
4-(dipropylamino)-N-acryloyloxy-N-methyl-3,5-dinitrobenzenesulfonamide
N-(4-(dipropylamino)-3,5-dinitrobenzenesulfonyl)-N-methoxycyclopropanecarboxamide
40 N-(4-(dipropylamino)-3,5-dinitrobenzenesulfonyl)-N-acetoxycyclopropanecarboxamide
1-(4-(dipropylamino)-3,5-dinitrobenzenesulfonyl)-1-allyloxy-3-methylurea
45 4-(allylethylamino)-N-methoxy-N-methyl-3,5-dinitrobenzenesulfonamide
4-(allylcyclopropylamino)-N-hydroxy-N-allyl-3,5-dinitrobenzenesulfonamide
N-(4-(allylethylamino)-3,5-dinitrobenzenesulfonyl)-N-50 hydroxyacrylamide
4-(diallylaminio)-N-acryloyloxy-N-methyl-3,5-dinitrobenzenesulfonamide
N-(4-(cyclopropylethylamino)-3,5-dinitrobenzenesulfonyl)-N-methoxycyclopropane-carboxamide
55 N-(4-ethylpropylamino)-3,5-dinitrobenzenesulfonyl)-N-acetoxymide
N-(4-(butylmethylamino)-3,5-dinitrobenzenesulfonyl)-N-hydroxyformamide

Preferred because of their especially effective herbicidal properties are those compounds in the subclass wherein R¹ is alkyl of up to 4 carbon atoms or alkenyl of up to 3 carbon atoms; R² is alkyl of up to 4 carbon atoms or cyclopropyl; Q is oxygen or sulfur with the proviso that when Q is oxygen R³ is hydrogen, alkyl of up to 3 carbon atoms or

70 wherein R⁵ represents alkyl of up to 3 carbon atoms, alkoxy of up to 3 carbon atoms or monoalkylamino of up to 3 carbon atoms and R⁴ is hydrogen, alkyl of up

to 4 carbon atoms, acyl of up to 3 carbon atoms, a lower alkali metal ion (Na, K or Li), or

wherein R^6 is alkyl of up to 3 carbon atoms; when Q is sulfur R^3 is

wherein R^7 represents alkyl of up to 3 carbon atoms and R^4 is trichloromethyl. Examples of such preferred herbicides are:

- 4-(dimethylamino)-N-hydroxy-3,5-dinitrobenzenesulfonamide
 4-(methylpropylamino)-N-ethoxy-3,5-dinitrobenzenesulfonamide
 N-acetoxy-N-(4-(dimethylamino)-3,5-dinitrobenzenesulfonyl)propionamide
 N-propoxy-N-(4-(dipropylamino)-3,5-dinitrobenzenesulfonyl)acetamide
 N-propionyloxy-N-(4-(butylethylamino)-3,5-dinitrobenzenesulfonyl)propionamide
 Sodium salt of 4-(diethylamine)-N-hydroxy-3,5-dinitrobenzenesulfonamide
 Potassium salt of 4-(butylethylamino)-N-hydroxy-3,5-dinitrobenzenesulfonamide
 4-(dimethylamino)-N-hydroxy-N-propyl-3,5-dinitrobenzenesulfonamide
 4-(diethylamino)-N-acetoxy-N-methyl-3,5-dinitrobenzenesulfonamide
 1-(4-(diethylamino)-3,5-dinitrobenzenesulfonyl)-1-methoxy-3-methylurea
 1-(4-(butylethylamino)-3,5-dinitrobenzenesulfonyl)-1-methoxy-3-propylurea
 O-ethyl-N-(4-(diethylamino)-3,5-dinitrobenzenesulfonyl)-N-(ethoxycarbonyloxy)carbamate
 N-(4-(diethylamino)-3,5-dinitrobenzenesulfonyl)-N-trichloromethylthio)acetamide
 N-(4-(dipropylamino)-3,5-dinitrobenzenesulfonyl)-N-(trichloromethylthio)propionamide
 4-(allylcyclopropylamino)-N-hydroxy-3,5-dinitrobenzenesulfonamide
 N-propionyloxy-Np(4-allylcyclopropylamino)-3,5-dinitrobenzenesulfonyl)acetamide
 N-propoxy-N-(4-(allylcyclopropylamino)-3,5-dinitrobenzenesulfonyl)acetamide
 O-methyl-N-(4-(allylcyclopropylamino)-3,5-dinitrobenzenesulfonyl)-N-(ethoxycarbonyloxy)carbamate
 N-(4-(allylcyclopropylamino)-3,5-dinitrobenzenesulfonyl)-N-(trichloromethylthio)acetamide

The compounds of the invention are solid at ambient temperature. They may be suitably formulated for use as herbicides, as wettable powders, dusts, granules, solutions, emulsifiable concentrates, emulsions and pastes. Wettable powders are usually compounded to contain 25, 50, 75 or up to 85% of toxicant and usually contain, in addition to solid carrier, 3-10% of a dispersing agent and, where necessary, 0-10% of stabilizer(s) and/or other additives such as penetrants or stickers. Dusts are usually formulated as a dust concentrate having a similar composition to that of a wettable powder but without a dispersant, and are diluted in the field with further solid carrier to give a composition usually containing 0.5-10% of toxicant. Granules are usually prepared to have a size between 10 and 100 BS mesh, and may be manufactured by agglomeration or impregnation techniques. Generally, granules will contain 0.5 to 25% of toxicant plus additives such as stabilizers, slow-release modifiers, binding agents, etc. Emulsifiable concentrates usually contain, in addition to the solvent and, when necessary, co-solvent, 10-50% s./v. toxicant, 2-20% w./v. emulsifiers and 0-20% of appropriate additives such as stabilizers, pen-

trants and corrosion inhibitors. Pastes are compounded so as to obtain a stable flowable product and usually contain 10-60% toxicant, 2-20% of appropriate additives and, as carrier, water or an organic liquid in which the toxicant is substantially insoluble. Except where indicated otherwise, all percentages given in this paragraph are percentages by weight.

For field application, the rate of application of the active agent may be varied from about 0.1 to 30 or more pounds per acre. It will be appreciated that the rate of application is subject to variation according to the particular active agent used, the particular species of plants involved and the local conditions; for example, temperature, humidity, soil moisture, chemical make-up soil and the like. Effective resolution of these factors is well within the skill of those versed in the herbicide art.

The herbicidal sulphydroxamic acids described by Formula I above may be prepared by reaction of a benzene-sulfonyl chloride of Formula II

20

25

II

wherein R^1 and R^2 are as defined above, with hydroxylamine. The reaction is suitably carried out in an aqueous tetrahydrofuran medium at a reaction temperature ranging from 5 to 25° C. with a reaction time of 0.1 to 2.5 hours. It has been found convenient to charge an excess of the hydroxylamine reactant to serve as an acceptor for the by-product hydrogen chloride which is generated by the reaction, however tertiary amines such as triethylamine or pyridine should also be suitable for this purpose.

The alkylated and/or alkenylated sulphydroxamic acid derivatives described by Formula I where Q is oxygen may be prepared by a reaction analogous to that described above for the sulphydroxamic acids, using as the hydroxylamine reactant, a substituted hydroxylamine of the Formula III

wherein one of R^3 and R^4 may be hydrogen and the other or, alternatively, both of R^3 and R^4 may represent the appropriate alkyl, cycloalkyl and alkenyl groups as described for Formula I above. The reaction proceeds under the same reaction parameters as described for the sulphydroxamic acid preparations, above.

The acylated sulphydroxamic acid derivatives described by Formula I wherein the hydroxamic nitrogen is substituted with an acyl and/or an acyloxy moiety may be prepared by reacting a sulphydroxamic acid or alkylated or alkenylated derivative wherein one of R^3 and R^4 is hydrogen prepared as described above with a carboxylic acid anhydride. This reaction is suitably carried out neat in an excess of carboxylic acid anhydride at reflux temperatures with a reaction time of 0.3 to 2.5 hours.

Reaction of a sulphydroxamic acid derivative of Formula I wherein R^3 is hydrogen with an alkyl isocyanate will yield the sulphydroxamic acid derivatives of Formula I wherein R^3 is a carbamoyl moiety. This reaction is suitably carried out under pressure in an ether solvent, at a reaction temperature of about 100° C., with a reaction time ranging from 6 to 18 hours.

The sulphydroxamic acid derivatives of Formula I wherein either or both of R^3 and/or R^4 is an alkyloxy-carbonyl moiety may be prepared by the reaction of a sulphydroxamic acid derivative of Formula I wherein R^3 and/or R^4 is hydrogen with an alkyl chloroformate. This reaction is suitably carried out in a tetrahydrofuran reaction medium at reaction temperatures ranging from ambient to 60° C. and reaction times of 1 to 3 hours.

The reaction is properly carried out in the presence of a base such as a tertiary amine, e.g., triethylamine, which serves as an acceptor of the by-product hydrogen chloride generated by the reaction.

The substituted benzenesulfonyl chlorides described by Formula II are known compounds and can be prepared from p-chlorobenzenesulfonic acid using a four-step synthesis scheme. In the initial reaction step the p-chlorobenzenesulfonic acid is nitrated in the 3 and 5 positions on the ring with a mixture of 90% nitric acid in 65% oleum. The dinitro intermediate is then converted to an alkali metal salt, e.g., sodium or potassium, by neutralization with the corresponding hydroxide and the salt compound is reacted with a secondary amine of the formula R^1R^2NH wherein R^1 and R^2 are as defined above to yield the alkali metal salt of a 4-(N,N -disubstituted amino)-3,5-dinitrobenzenesulfonic acid. This alkali metal salt is then converted to the corresponding sulfonyl chloride by treatment with phosphorus pentachloride in a solution of phosphoryl chloride.

The thiohydroxamic acid derivatives of this invention, i.e., the compounds of Formula I wherein Q is sulfur, may be prepared by the reaction of an acylated benzenesulfonamide of Formula IV.

IV

with a polyhaloalkylsulfinyl chloride of the formula

wherein X is chlorine or fluorine and N is 1 or 2. This reaction is suitably carried out in a dioxane reaction medium at reaction temperatures ranging from ambient to 50° C. with a reaction time of from 5 to 20 hours. The reaction is properly carried out in the presence of a base such as a tertiary amine e.g., triethylamine, which serves as an acceptor for the by-product hydrogen chloride generated by the reaction.

The acylated benzenesulfonamides of Formula IV may be prepared by reacting the unacylated analogs with an acid anhydride of the formula

wherein R^6 is as defined above. The reaction is suitably carried out neat, or in an aromatic solvent such as xylene, at reflux temperatures with reaction times of from 1 to 2 hours. These unacylated benzenesulfonamide analogs are known compounds, e.g., see U.S. Pat. 3,367,949.

The compounds of the invention, processes for their preparation and their herbicidal activity, are illustrated by the following examples, in which parts by weight (w.) and parts by volume (v.) bear the same relation as the kilogram to the liter and all temperatures are in degrees centigrade. The structures of the compounds, whose preparation is described in the following examples, were confirmed by infrared spectrum, nuclear magnetic resonance and elemental analysis.

EXAMPLE I

4-(dipropylamino)-N-hydroxy-3,5-dinitrobenzenesulfonamide

5

10

A solution of hydroxylamine in water was prepared by the dropwise addition (5 minutes) of a cold solution of 16 w. of sodium hydroxide in 50 v. of water to a solution of 27.8 w. of hydroxylamine hydrochloric acid salt in 100 v. of water at 5-10°. This mixture was stirred during the rapid (30 seconds) addition of a solution of 18.8 w. of 3,5-dinitro-4-(dipropylamino)benzenesulfonyl chloride in 50 v. of tetrahydrofuran at 5-10°. The reaction mixture was stirred for 5 minutes and then phase separated. The aqueous layer was extracted with two portions (75 v.) of ether. The combined extracts were dried over anhydrous magnesium sulfate, filtered and concentrated to a red oil which crystallized on standing to yield 25 an orange crystalline solid, 4-(dipropylamino)-N-hydroxy-3,5-dinitrobenzenesulfonamide (16.6 w.) melting at 185° (with decomposition).

EXAMPLE II

30 Sodium salt of 4-(dipropylamino)-N-hydroxy-3,5-dinitrobenzenesulfonamide

35

40 4-(dipropylamino)-N-hydroxy-3,5-dinitrobenzenesulfonamide (2.6 w.) prepared as in Example I was added to a solution of sodium methoxide (0.4 w.) in methanol (75 v.). The reaction mixture was concentrated to dryness to give an amorphous, water soluble, red solid, sodium salt of 4-(dipropylamino)-N-hydroxy-3,5-dinitrobenzenesulfonamide (2.5 w.) which decomposed on heating to 110°.

EXAMPLE III

50 N-acetoxy-N-(4-(dipropylamino)-3,5-dinitrobenzenesulfonyl)-acetamide

55

60

65 A mixture of 4-(dipropylamino)-N-hydroxy-3,5-dinitrobenzenesulfonamide (6.0 w.), prepared as in Example I, and 50 v. of acetic anhydride was heated to reflux for 30 minutes. The reaction mixture was concentrated under vacuum. The residue was dissolved in 250 v. of ether, washed with aqueous sodium hydrogen carbonate, and dried over anhydrous magnesium sulfate. Concentration of the ether solution gave an orange viscous oil which was crystallized from a solvent mixture of ether (3 parts) and pentane (1 part) to afford an orange-yellow crystalline solid, N-acetoxy-N-(4-(dipropylamino)-3,5-dinitrobenzenesulfonyl)acetamide (7.0 w.) melting at 89-91°.

70

75

EXAMPLE IV

1-(4-(dipropylamino)-3,5-dinitrobenzenesulfonyl)-1-methoxy-3-methylurea

4-(dipropylamino)-N-methoxy - 3,5 - dinitrobenzenesulfonamide (14.0 w.) prepared according to the technique described in Example I using methoxyamine as the amine reactant was charged into a glass cylinder containing a mixture of methyl isocyanate (5 v.) and ether (200 v.). The cylinder was sealed and placed on a steam bath for 18 hours. The reaction mixture was chilled in an ice bath and filtered to yield a yellow crystalline solid, 1-(4-(dipropylamino)-3,5-dinitrobenzenesulfonyl)-1 - methoxy-3-methylurea melting at 160-163° and 171-174°.

EXAMPLE V

Ethyl N-(4-dipropylamino)-3,5-dinitrobenzenesulfonyl-N-(ethoxycarbonyloxy)carbamate

Triethylamine (2.2 w.) was added to a solution of 4-(dipropylamino)-N-hydroxy - 3,5 - dinitrobenzenesulfonamide (3.6 w.), prepared as in Example I, in tetrahydrofuran (100 v.). The resulting dark solution was stirred during the dropwise addition (3 minutes) of 2.4 w. of ethyl chloroformate. This addition was exothermic to 45° and caused the color to change to a light yellow with solid suspended. The mixture was heated to 60° for 1.5 hours and then poured into ice water. The product was extracted with 3× 100 v. of methylene chloride and dried over anhydrous magnesium sulfate. Evaporation of the solvent gave 2.5 w. of red oil which was crystallized from ether to yield a yellow crystalline solid, ethyl N-(4-(dipropylamino) - 3,5 - dinitrobenzenesulfonyl) - N-(ethoxycarbonyloxy)carbamate melting at 104-107°.

EXAMPLE VI

N-(4-dipropylamino)-3,5-dinitrobenzenesulfonyl-N-(trichloromethylthio)acetamide

4-(dipropylamino)-3,5 - dinitrobenzenesulfonamide (10 w.) was added to acetic anhydride (25 v.), and the mixture was heated at reflux for two hours. The volatile impurities were removed by distillation in a vacuum, and ice water was added to the residue. After stirring and scratch-

ing a yellow solid crystallized out of solution. The solid product was filtered, washed with water and dried. The product was then recrystallized from an ether-hexane mixture and dried in a vacuum, to yield N - (4 - (dipropylamino) - 3,5 - dinitrobenzenesulfonyl)acetamide (8.9 w.) melting at 148-149°. The structure was confirmed by elemental and IR analyses.

To a solution of 7.8 w. of N-(4-(dipropylamino)-3,5-dinitrobenzenesulfonyl)acetamide and 2.0 w. of triethylamine in 40 v. of dioxane was added dropwise at 10° with stirring a solution of 2.7 v. of trichloromethanesulfenyl chloride in 20 v. of dioxane. The mixture was stirred at ambient temperature for 3 hours and left standing for 16 hours. The reaction mixture was poured over ice water, extracted with 2× 150 v. of methylene chloride. Drying ($MgSO_4$) and evaporating the solvent gave a brown yellow viscous oil which upon trituration with ethanol yielded a yellow crystalline solid, N-(4-dipropylamino)-3,5-dinitrobenzenesulfonyl-N - (trichloromethylthio)acetamide (6.0 w.) melting at 111-114°. The structure was confirmed by NMR, IR and elemental analyses.

Analysis.—Calculated (percent): C, 33.5; H, 3.5; N, 10.4. Found (percent): C, 33.8; H, 3.9; N, 10.8.

EXAMPLE VII

Following procedures similar to those given in previous examples, the following other species of the compounds of the invention were prepared (Symbols refer to formula V). In all cases the identity of the compounds was established by elemental, IR and/or NMR analyses.

EXAMPLE VIII

Pre-emergence herbicidal activity of the typical compounds of the invention was evaluated by planting weed

seeds in soil held in large test tubes, the soil having been treated with the test compound at the rate of 1 and 10 milligrams of test compound per tube, respectively. Seeds of water grass (*Echinochloa crusgalli*) and cress (*Lepidium sativum*) were germinated in treated soil under controlled conditions of temperature and light for 12 to 13 days prior to evaluation of the effectiveness of the treatments. At that time, the germination was noted and the treatments were rated on a 0 (no effect) to 9 (all dead) scale. The results are summarized in Table II.

We claim as our invention:

1. A compound defined by the formula:

wherein R^1 , R^2 and R^3 are the same or different and each is alkyl of 1 to 4 carbon atoms and R^4 is perchloro- or perfluoro-alkyl of 1 to 2 carbon atoms.

2. The compound according to claim 1 wherein R^1 and R^2 each is propyl, R^3 is methyl and R^4 is trichloromethyl.

Post-emergence herbicidal activity was evaluated by spraying dilute suspensions of the test compound in a 1:1 mixture of acetone and water with 0.5% wetting agent on crabgrass (*Digitaria sanguinalis*) and pigweed plants (*Amaranthus sp*) grown under controlled conditions at the rate of 1 and 10 pounds test compound per acre. After the plants were held for 10 to 11 days, they were rated for treatment effect on a 0 (no effect) to 9 (total plant kill) scale. The results of these test are shown in Table II.
